(57) **CLAIM**

The ornamental design for a reflex sight device, as shown
and described.

DESCRIPTION

FIG. 1 is a perspective view of the reflex sight device
showing my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a rear elevational view thereof;

FIG. 7 is a perspective view thereof when a lens is attached
to the reflex sight device; and,

FIG. 8 is a rear elevational view of FIG. 7.

The broken lines show portions of the reflex sight device that
form no part of the claimed design.
